SHOE CABINET

Everett Lorne Whenham, Los Angeles, Calif.

Application February 10, 1931, Serial No. 514,758

1 Claim. (Cl. 211—35)

My invention relates to shoe cabinets and particularly to cabinets of this class for supporting shoes in out-of-the-way, though readily accessible, positions.

5 The objects of this invention are: first, to provide a cabinet of this class whereby many shoes may be stored in out-of-the-way positions in and upon which the shoes may be easily and quickly placed, from which the shoes may be easily and quickly removed, and in which the shoes are not readily disturbed when placed or supported therein or thereon; second, to provide a cabinet of this class from which the shoes cannot be readily displaced or shaken by the shaking or moving of the cabinet, or by vibration of the building in which the cabinet is mounted; third, to provide a very simple shoe supporting and storing cabinet, one which is very economical to construct, one which is durable and which will not readily get out of order; fourth, to provide a cabinet of this class which, though relatively small in size, will support many various styles, types and sizes; fifth, to provide a novel embodiment of the aforementioned features in a simple cabinet which may be supported and built in a thin wall of a building and flush with the face of the wall; sixth to provide a cabinet of this class which is constructed as to take up substantially the maximum space between the studs of a building wall; and, seventh, to provide a novel, simple and efficient means of securing and supporting the shoe supporting elements upon and within the cabinet.

With these and other objects in view, as will appear hereinafter, I have devised a shoe supporting cabinet having certain novel features of construction, combination and arrangement of parts and portions as will be hereinafter described in detail and particularly set forth in the appended claim, reference being had to the accompanying drawing and to the characters of reference thereon which form a part of this application in which:

Figure 1 is a perspective view of my shoe supporting cabinet in its preferred form supported and constructed in the wall of a building, the wall being shown fragmentarily; Fig. 2 is a sectional elevational view thereof taken through 2—2 of Fig. 1; Fig. 3 is a transverse sectional view thereof, taken through 3—3 of Fig. 1; Fig. 4 is an enlarged fragmentary sectional view thereof, taken through 4—4 of Fig. 2, showing in detail the method of supporting and securing the shoe supporting elements within the cabinet and on the walls thereof; and, Fig. 5 is a

fragmentary perspective view of one end of one shoe supporting element.

Like characters of reference refer to similar parts and portions throughout the views of the drawing.

The enclosing casing or cabinet 1 of my shoe supporting means, in the embodiment of my invention shown in the drawing, may be of various sizes and shapes. This casing or enclosure is, however, relatively high or long with respect to its lateral dimensions when the cabinet is constructed to be inserted or supported in the wall of a building. The width of the casing or enclosure is such that the same may be readily placed between two adjacent studs 2, of conventional spacing, in the wall of a building. The height of the casing may vary considerably depending upon the number of shoes desired to be stored in the cabinet, the shoes being supported in superimposed horizontal rows. The casing is 20 preferably made of sheet metal and in a unit so that the cabinet may be readily and bodily inserted into an opening in a wall and secured to the wall.

The casing, as shown, consists of a back wall 1a, side walls 1b and upper and lower end walls 1c. The front side of the cabinet is preferably open as shown in the drawing. The front edges of the side and end walls are provided with outwardly extending flanges 3 which may be positioned against the outer side of the plaster surrounding the wall opening, said flanges providing means for securing the cabinet to the wall. Against the outer sides of the flanges is secured a suitable molding 4 for concealing the flanges and the means for securing the flanges to the wall.

The means for supporting the shoes in the cabinet, as shown in the drawing, consists of a plurality of pairs of spaced apart horizontal rods 5 and 6, which, for ordinary purposes, may be approximately three-sixteenths of an inch in diameter. The rod 5 is positioned above the rod 6 and slightly backwardly from the vertical plane passing through the rod 6. The shoes are suspended from the upper rod of each pair of rods and rest against the outer side of the lower rod. The shoes are supported by placing or hooking the heel of the shoe over the upper rod and allowing the shoe to be suspended therefrom and to rest with the sole of the shoe against the outer side of the lower rod, substantially as shown in Fig. 2. The upper rods 5 are spaced outwardly from the back wall a sufficient distance so as to allow the heel of the shoe to 55

overhang backwardly between the rod and the back wall. In the case of ladies' shoes with high heels, the bottoms of the heels rest against the back walls. The lower rods 6 are so positioned that the shoes are supported at an angle with the tips of the shoes outwardly but wholly within the cabinet or the enclosing casing of the cabinet. When the shoes are so supported, they cannot be readily shaken from the supporting means by vibration or shaking of the cabinet, or when other shoes are removed or placed thereon, or when the shoes are accidentally touched or struck. With such arrangement of shoe supporting means with respect to the enclosing casing, the casing may be made of such depth from front to rear as to fit into a residence building wall of common thickness without projecting beyond the front face thereof.

The rods 5 and 6 serve also as horizontal spacers between the side walls 1b, holding these walls from being compressed readily toward each other or drawn away from each other, that is, the rods serve as compression and tension reinforcing members. The ends of the rods abut against the inner sides of the side walls and are secured thereto by prongs which extend beyond the ends of the rods as bifurcated portions. The securing means is affected by welding staples 7 to the inner sides of the rods in such manner that the pointed portions of the staples extend beyond the ends of the rods, as shown best in Figs. 4 and 5. These pointed portions extend through spaced apart holes 1d in the side walls 1b and are bent over against the outer sides of the side walls, as shown best in Figs. 2 and 4. Thus, the rods are secured at their ends against longitudinal movement with respect to the side walls and

are also secured to the side walls against rotation. The pointed portions of the staples when bent against the outer sides of the side walls also take up little space so that the overall width of the cabinets, except for the front flanges, need be only slightly less than the space between adjacent wall studs in order to place the same between conventionally spaced studding. When the casing is made of sheet metal and constructed as herein specified, the greatest available shoe storing space is provided for conventional building wall construction without cutting the studs.

Though I have shown and described a particular construction, combination and arrangement of parts and portions of my shoe cabinet, I do not wish to be limited to this particular construction, combination and arrangement, but desire to include in the scope of my invention the construction, combination and arrangement substantially as set forth in the appended claim.

Having thus described my invention, what I claim as new and desire to secure by Letters Patent is:

In a means of the class described, an enclosure, rods extending between the opposite side walls of the enclosure, the ends of the rods abutting against the inner sides of the side walls, and a staple secured to each end of said rods, the pointed portions of the staples extending beyond the ends of the rods and through correspondingly spaced apart holes in the opposite sides of the enclosure, said pointed portions being bent against the outer sides of said side walls, said rods forming compression and tension members between the opposed side walls.

EVERETT LORNE WHENHAM.
